UNITED STATES PATENT OFFICE.

CLAUDE E. PECK, OF DIAMOND, INDIANA, ASSIGNOR OF ONE-HALF TO
WILLIAM WOLBERG, OF BRAZIL, INDIANA.

SPOOL-HOLDER.

SPECIFICATION forming part of Letters Patent No. 591,178, dated October 5, 1897.

Application filed February 10, 1897. Serial No. 622,867. (No model.)

To all whom it may concern:

Be it known that I, CLAUDE E. PECK, a citizen of the United States, residing at Diamond, in the county of Parke and State of Indiana, have invented certain new and useful Improvements in Thread-Holders; and I do declare the following to be a full, clear, and exact description of the invention, such as will enable others skilled in the art to which it applies to make and use the same.

My invention relates to a thread-holder, and more particularly to that class of inventions intended to be attached to the garment of the seamstress and hold for ready use a spool or spools containing different-colored threads.

The object of the invention is to provide a device of this character which shall be simple of construction, durable in use, and comparatively inexpensive of production, and which may be easily attached to or removed from the garment of the user.

With this object in view the invention consists of certain features of construction and combination of parts, which will be herein-after fully described and claimed.

In the accompanying drawings, Figure 1 is a view showing the holder attached to a fragment of a garment, and Fig. 2 is a rear view. 1 denotes the supporting-plate, which may be suitably inscribed or ornamented, and to the back of which is secured, one above the other, two spring-pins 2 and 3 of usual and well-known construction.

4 denotes the spool-hanger, which is made from a single piece of wire bent to form the horizontal rod 5, the ends of which are formed with eyes 6, through which the pin 3 projects, and said eyes terminate in two vertical arms

7, one of which is formed with a hook 8 and 40 the other of which is formed with a spring-eye 9 and then extends laterally at 10 parallel with the rod 5 and has its free end engaged with the hook 8. Upon this lateral portion 10 of the hanger any desired number 45 of spools may be placed, and they will always be within convenient reach.

If desired, I may make the device on an enlarged scale and adapted to hold a ball of 50 yarn.

Having thus fully described my invention, what I claim as new and useful, and desire to secure by Letters Patent of the United States, is—

A spool-holder consisting of a plate having 55 a safety-pin permanently attached near the upper edge of the reverse side thereof for connecting the plate to the clothing of the wearer, and a separate supporting device secured below the safety-pin on the same side 60 of the plate, said supporting device comprising a piece of wire doubled upon itself to form parallel members, one of said members being attached to the plate and the other member forming a detachable support for 65 the spool-holder, a keeper on the attached member, and a spool-holder comprising a rectangular frame having eyes at its upper corners for connection to the support, and a bar 70 for holding the spools detachably connected by a keeper or guard to one of the end bars of said holder, substantially as described.

In testimony whereof I hereunto affix my signature in presence of two witnesses.

C. E. PECK.
